(57) **CLAIM**

The ornamental design for a headlamp cover lens, as shown and described.

DESCRIPTION

FIG. 1 is a top isometric view of a headlamp cover lens, showing a first embodiment of our new design.

FIG. 2 is a bottom isometric view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a top isometric view of a headlamp cover lens, showing a second embodiment of our new design, which is a mirror image of the headlamp cover lens shown in FIGS. 1-8.

FIG. 10 is a bottom isometric view thereof.

FIG. 11 is a front elevational view thereof.

FIG. 12 is a rear elevational view thereof.

FIG. 13 is a right side elevational view thereof.

FIG. 14 is a left side elevational view thereof.

FIG. 15 is a top plan view thereof; and,

FIG. 16 is a bottom plan view thereof.

Stippling in the drawings represent the contours of the design, and is not intended to indicate surface decoration. The broken lines shown in the drawings depict portions of the headlamp cover lens that form no part of the claimed design.
